CLAIM

I claim the ornamental design for a grate, as shown and described.

DESCRIPTION

FIG. 1 is a perspective view of a first embodiment of a grate showing my new design, shown in an environment of use on a grill;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a bottom plan view thereof;

FIG. 8 is a front elevation view of the grate in FIG. 1, the rear elevation view being an identical view thereof;

FIG. 9 is a right side elevation view thereof, the left side elevation view being an identical view thereof;

FIG. 10 is a perspective view of a second embodiment of the grate shown in an environment of use on a grill;

FIG. 11 is a top plan view thereof;

FIG. 12 is a front elevation view thereof;

FIG. 13 is a right side elevation view thereof;

FIG. 14 is a rear elevation view thereof;

FIG. 15 is a left side elevation view thereof;

FIG. 16 is a bottom plan view thereof; and,

FIG. 17 is a front elevation view of the grate in FIG. 10. The broken line showing of the grill illustrates environments and forms no part of the claimed design.
